United States Patent Office

Des. 223,969

Patented June 20, 1972

223,969

ELECTRICALLY-POWERED ERASER OR THE LIKE

Francesco Collura, New York, N.Y., assignor to Keuffel
& Esser Company, Morristown, N.J.

Filed Dec. 22, 1970, Ser. No. 26,614

Term of patent 14 years

Int. Cl. D19—02

U.S. Cl. D74—7

FIG. 1

FIG. 2

FIG. 3

FIG. 4

FIG. 5

FIG. 6

FIG. 1 is a perspective view taken from the front and left side of an electrically powered eraser embodying my new design, as it appears without the eraser element.

FIG. 2 is a top plan view thereof;

FIG. 3 is a left side elevational view, the right side being substantially a mirror image thereof;

FIG. 4 is a bottom plan view thereof;

FIG. 5 is a front elevational view thereof; and

FIG. 6 is a rear elevational view thereof.

I claim:

The ornamental design for an electrically-powered eraser or the like, as shown and described.
